DISPENSING CABINET

Antonio Galante, Medford, Mass.

Application December 5, 1934, Serial No. 756,065

4 Claims. (Cl. 242—55.2)

This invention relates to dispensing cabinets and has for an object to provide a cabinet particularly suitable for holding a roll of sheet material such as waxed paper and facilitating the removal from the cabinet of any desired length of such material at one time, and the severing of such length from the remainder of the roll.

A further object is to provide a cabinet such that the roll is protected from access of dust or contaminating substances, so that the material is maintained in strictly sanitary condition until used.

A still further object is to provide such a cabinet of pleasing and somewhat ornamental appearance which may be secured to a wall or other suitable support in a kitchen or pantry in convenient position.

Further objects and advantageous constructions will appear from a more complete description of an embodiment of this invention shown in the accompanying drawing in which

Figure 1 is a perspective view of the cabinet in partly open position.

Figure 2 is a detail section on line 2—2 of Figure 1.

Figure 3 is a detail section on line 3—3 of Figure 2.

Figure 4 is a detail section on line 4—4 of Figure 1, but showing the cabinet closed.

Figure 5 is a view similar to Figure 4, but showing the cabinet open.

Referring to the drawing, the device comprises a casing having a pair of circular end members 1 joined around a portion of their peripheries by a side wall member 2. Each of the end members 1 is provided with a peripheral portion 3 substantially U-shaped in cross section and having its outer margin formed into a rounded bead 4. The open sides of these U-shaped portions of the two end members 1 face each other so that the ends of the side wall member 2 may be extended thereinto and secured by any suitable means such as spot welding, soldering, brazing, or the like.

The side edges of the wall member 2 terminate spaced apart as shown best in Figure 4, the upper edge being turned upwardly as at 5 and folded over against itself as at 6 to form an upstanding rib with a rounded exposed edge as at 7, which acts both as a stiffener for the cabinet, and also as a stop for the cover member. This cover member 10 is formed as a curved piece having its ends as at 11 extended into and slidable within the U-shaped portions 3 and it is of sufficient width so that it may entirely bridge the opening between the side edges of the side wall member 2.

The lower edge of the side wall member 2 is extended outwardly as at 12 to form a flange or shelf and its margin is then upwardly turned to present an edge member 13 to sheet material 14 unwound from a supply roll 15. The portions 12 and 13 provide a stiffening angle member extending substantially the length of the cabinet. This supply roll is positioned within the casing, being inserted between the upper and lower side edges of the member 2 when the cover 10 is open. 5 This cover 10 has its lower edge portion outwardly extended in a flange as at 20 and then downturned as at 21 to form a clamping portion which may engage the upper face of the material 14 and press it against the extension 12 inwardly 10 of the edge member 13. The portions 20 and 21 act as a stiffening angle member which tends to hold the edge of the cover against distortion so that it will properly cooperate with the portions 12 and 13 of the casing side wall member, even 15 though the cover is of relatively thin, light sheet material. The cover member 10 is provided with a suitable handle member 22 which may be secured to the portion 20 as by spot welding or the like, and this handle not only facilitates the 20 opening of the cover member 10 in sliding it upwardly and rearwardly, but it also permits the clamping member 21 to be held in clamping engagement with the material 14 so that by grasping the extended portion 14 of the sheet material 25 which is to be dispensed, this material may be torn off along the upper edge of the portion 13. The cabinet may be secured to a wall or other suitable support, and for this purpose it is shown as provided at each end with a bracket 30 member 25. Each bracket member may be provided with an outwardly extending foot 26 to receive fastening means such as screws 27 to secure it to a wall or other support, and it is provided with a concaved forward face as 28 (see 35 Figure 3) which may be engaged about the outer face of the rib portion 3 and be secured thereto or to the bead 4, or both, as by spot welding or the like. The portions 5 and 6 along the edge 40 of the side wall member 2 may be provided with a notch 30 at each end engaging over the bead 4. The portion 12 may be formed similarly and the cover extension 20 may also be provided with notch openings at each end through which the bead 4 is slidable as the cover is moved.

The provision of the U-shaped marginal portion 3 of the end members 1 produces an ornamental inwardly dished effect to these ends which adds to the appearance of the cabinet, which may be enameled or otherwise finished 55

to harmonize with the finish of the wall or other member on which it is supported.

From the foregoing description of an embodiment of this invention, it should be evident to those skilled in the art that various changes and modifications might be made without departing from the spirit or scope of this invention as defined by the appended claims.

I claim:

- 10 1. A device of the class described comprising a casing having an open side portion provided along one edge with a stiffening flange having an outwardly extended edged member over which sheet material projecting from said casing may extend and be torn off, and a cover for said open side portion having a stiffening flange along an edge and provided with a portion positioned to clamp the material against said side portion flange back from its edge to facilitate such tearing.
- 15 2. A device of the class described, comprising a tubular casing having an open side portion through which a roll of sheet material may be inserted thereinto, and having a stiffening member along one edge of said side portion presenting an edge over which an unwound portion of said material extending outwardly of said casing may be engaged and torn off by exerting pull on said portion, a cover slidably guided in
- 20 30 said casing between open and closed positions relative to said open side portion, said cover having a stiffening member along its edge provided with a portion for clamping said material against said side portion stiffening member inwardly of its edge when said cover is closed to hold back the material in said casing during such pulling, and means for securing said casing to a support.
- 25 35 3. A device of the class described, comprising a casing having a pair of spaced end members provided with circular peripheral portions U-shaped in cross section with their open sides oppositely disposed and having marginal peripheral beads, a curved side wall having its ends secured

within said U-shaped portions and having its side edges spaced apart to form an opening through which a roll of sheet material may be inserted within said casing, the lower of said side edges being extended outwardly and its margin turned upwardly, a curved cover member having its ends slidable within said U-shaped portions and movable to and from a position closing said opening, the lower edge of said cover being extended downwardly and outwardly to 10 press said sheet material against the outwardly extending portion of said side wall back of its upwardly extending margin, said outwardly extended cover edge having an opening at each end through which said beads extend, a handle secured to said cover, and means for supporting said casing.

4. A device of the class described, comprising a casing having a pair of spaced end members provided with circular peripheral portions U-shaped in cross section with their open sides oppositely disposed and having marginal peripheral beads, a curved side wall having its ends secured within said U-shaped portions and having its side edges spaced apart to form an opening 20 through which a roll of sheet material may be inserted within said casing, the lower of said side edges being extended outwardly and its margin turned upwardly, the upper of said side edges being bent to form a stiffening element extending between said end members, a curved cover member having its ends slidable within said U-shaped portions and movable to and from a position closing said opening, the lower edge of said cover being extended downwardly and outwardly to 30 press said sheet material against the outwardly extending portion of said side wall back of its upwardly extending margin, said outwardly extended cover edge having an opening at each end through which said beads extend, a handle secured to said cover and means for supporting said casing.

ANTONIO GALANTE.
